UNITED STATES PATENT OFFICE.

ETIENNE FAJON, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,480, dated November 28, 1882.

Application filed September 23, 1882. Term of patent 3½ years.

To all whom it may concern:

Be it known that I, ETIENNE FAJON, of Boston, in the county of Suffolk and State of Massachusetts, have invented a new and original 5 Design for Carpets, of which the following is a specification.

The nature of my design is fully shown in the accompanying photographic illustration.

The design is composed of the architectural 10 figure A, comprising an archway and steps leading therefrom, the partly-circular figures B C, the bouquets B' C', partly covering the figures B C, and the various minor foliage ornamentation, all as shown.

I claim—

The design for a carpet, substantially as 15 shown and described.

In testimony whereof I have signed my name to this specification, in the presence of two subscribing witnesses, this 6th day of September, 20

A. D. 1882.

ETIENNE FAJON.
